UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,724.

Specification of Letters Patent.

Patented July 21, 1908.

Application filed April 21, 1906. Serial No. 313,070.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

This invention is concerned with calculating machines including calculating typewriter attachments.

In a previous application filed August 25, 1905, Serial No. 275,780, I have shown a machine having a totalizer and means for determining whether at any given printing point the totalizer shall add, subtract or not operate, in other words, a machine in which the operator can decide beforehand whether, when the carriage is at the right column, the totalizer shall operate or not, and if so in which direction. In that machine there are two master or setting wheels located opposite to (that is, in line with) each other, one for addition and the other for subtraction; and the totalizer passes between them and is capable of swinging into engagement with one or the other of them or occupying an intermediate position out of engagement with either of them. The present machine differs from the other in that although the master wheels are arranged in pairs, the two wheels of any pair are laterally offset so that the totalizer wheel can be in line with only one of them at a time and may also occupy a position between them, in which position no rotary motion is transmitted to the totalizing wheels. In the same respect this present machine differs from the one for which I filed application for Letters Patent December 22, 1905, Serial No. 292,932.

The object of my present invention is to produce the same final results as in the two aforesaid previous inventions but without the necessity of moving either the totalizer or the master wheels transversely to the direction of travel of the totalizer or transversely to the axis of the rotation of the master wheel.

I attain my object by the mechanism illustrated in the accompanying drawings in which:

Figure 1 is a general front elevation of a typewriter attachment embodying my invention. Fig. 2 is a front elevation upon somewhat larger scale showing the arrangement of the totalizer, the master wheels and

the controlling device. Fig. 3 is a sectional view taken on line 3—3 Fig. 2. Figs. 4, 5 and 6 are enlarged sectional views taken on line 5—5 Fig. 2 showing the different positions of the controlling pins, and the corresponding effects upon the controlling lever. Figs. 7 to 14 illustrate the interior construction of the totalizer. Fig. 7 is a front assembly view partly in section showing the relation of the different totalizer parts. Fig. 8 is a view similar to Fig. 7 but showing the different pieces spaced somewhat apart to better show their construction. Fig. 9 is a sectional view of the intermediate wheel located farthest to the right in the totalizer. Fig. 10 is a sectional view taken on line 10—10 Fig. 7. Figs. 11, 12, 13 and 14 are side views of component parts of the totalizer.

Like numerals denote like parts throughout the drawings.

In the typewriter, the stationary framework 1 supports a traveling carriage 2 which has a step by step escapement under the action of the keys 3. A differential or valuating mechanism 4 is provided for transmitting motion to the master wheels 5 and 6 and although the form of differential mechanism is non essential, a suitable one is shown in Patent 782,554 granted to me Feb. 14, 1905. The means of transmitting motion from the differential mechanism to the master wheel is also non essential but in the construction here shown said differential mechanism operates the shaft 7 which is gear connected to each of the two master shafts 8 and 9, said shafts being journaled in the stationary brackets 10. Said transmission gearing is preferably mounted on the stationary platform 11. Shafts 8 and 9 are parallel with the direction of travel of the carriage 2 and the master wheels 5 and 6 respectively are rigidly fastened to them. Said master shafts and master wheels are so located and proportioned with reference to the accumulating wheels 27 of the totalizer that when an accumulating wheel is in line laterally with a master wheel the two will become enmeshed.

The totalizer travels in unison with the carriage but is transversely immovable. This is accomplished in the present design by mounting the totalizer upon a rectangular bar 12 rigidly supported upon a slide 13 which is slidably mounted upon a stationary bar 14. An arm 15 extends from the car-

riage to slide 13 to transmit motion from the former to the latter. Within certain limits the totalizer is slideable along bar 12 under the action of a controlling lever hereinafter described but with this exception the totalizer travels in unison with the carriage.

The construction of the totalizer will be described hereinafter but for the present it is sufficient to say that the wheels 27 of the totalizer, which are the ones which mesh with the master wheels in traveling past them, are comparatively thin as are also said master wheels and that said master wheels when viewed from the front of the machine (Figs. 1 and 2) are laterally offset from each other so that a totalizer wheel 27 may occupy a position laterally beneath them without engaging either of them. From this intermediate position a slight movement of the totalizer toward the right along bar 12 will bring the aforesaid accumulating wheel into mesh with one of the setting wheels, and a slight movement toward the left will bring said totalizer wheel into mesh with the companion master wheel on the other shaft. Shafts 8 and 9 rotate in opposite directions, and as they and their master wheels engage opposite sides of the totalizer wheels, the master wheel on one shaft will produce addition and on the other shaft will produce subtraction. Hence the totalizer will either remain at rest or will add or subtract depending upon whether it stops with one of its wheels in an intermediate position between two companion master wheels or at a point slightly to the left or to the right of such intermediate position.

The control of the position of the totalizer laterally upon its supporting bar 12 is effected by means of a controlling device which constitutes one of the features of this invention and will now be described: A bell crank lever having a vertical arm 16 and an approximately horizontal arm 17 is pivoted to the arm 18 rigidly fastened to bar 12 or any other part moving in unison therewith. A link 19 connects the free end of arm 16 to the totalizer and the parts are so arranged that the vertical movement of the free end of arm 17 causes a slight shifting of the totalizer lengthwise of bar 12, this shifting however being sufficient to bring an accumulating wheel 27 into line to mesh with one or the other of a pair of master wheels or to a point between them. The vertical movement of the free end of arm 17 is accomplished by means of controlling pins 20 mounted in pin holders 21 on bracket 11, said pins being adapted to act upon any of the three cam surfaces 17^a, 17^b or 17^c upon the underside of said arm. Said three cam surfaces 17^a, 17^b and 17^c all have a different pitch with respect to the horizontal and they are so formed that when the totalizer is traveling from right to left, as in the normal action of the machine, the lowest cam

surface 17^a will shift the totalizer farthest along bar 12, the middle surface 17^b will shift it a less distance and the surface 17^c will shift it least or may be designed, as I prefer, to shift it not at all. As a result when the top of a pin 20 contacts the bottom of surface 17^a the totalizer will be shifted along bar 12 opposite to a master wheel, say for example one which subtracts, and when the top of pin 20 contacts surface 17^c no shifting action of the totalizer along bar 12 will occur but said totalizer will remain fixed with reference to said bar, the totalizer in this position being opposite to the remaining one of a pair of master wheels, for example the adding master wheel. The preferred construction is the one in which the surface 17^c has zero pitch, that is to say normally lies horizontal, for by this construction the totalizer may normally remain in say addition position upon bar 12 (addition being the commonest operation) and need be shifted only when it is desired that the totalizer shall remain non active or shall subtract; for it is obvious that by having the totalizer remain normally in adding position on bar 12, and shifting it along said bar only when subtraction or non action is desired, the surface 17^c may be omitted entirely and only two cam surfaces be employed. In the present drawings I have shown only single acting cam surfaces instead of double positive acting ones, which might be provided if desired, and for the purpose of coöperating with the single acting cams a spring 22 is provided for maintaining arms 17 in close contact with pins 20. In the structure shown this spring is a compression spring interposed between the totalizer and the arm 18.

An advantageous design of pin is the one shown in detail in Figs. 4, 5 and 6 in which the pin proper is formed upon the base 20^a which is rectangular in horizontal cross sections and removably fits into pockets in a pin holder 21. The pin is formed eccentrically upon its base when viewed from one side and centrally when viewed transversely, from another side, with the result that by turning the pin around, that is, placing it in different positions in the pocket of the pin holder, the pin will occupy a rearward, forward, or intermediate position to contact surface 17^c as shown in Fig. 4 or 17^a as shown in Fig. 4 or 17^a as shown in Fig. 6 or 17^b as shown in Fig. 5. By this construction a single pin may serve by preadjustment to shift the totalizer along bar 12 to adding, subtracting or non acting position. A pin of similar construction is shown in the aforesaid previous application Serial No. 275,780 filed August 25, 1905, and is not here claimed. When a plu-

70 75 80 85 90 95 100 105 110 115 120 125 130

rality of totalizers are to be employed it is desirable to employ also a plurality of pin holders and arrange them side by side as shown in Fig. 3. By this means each cam arm 17 may travel along its own set of pins 20 and thus give each totalizer an independent action. This feature is also shown in said application Serial No. 275,780.

The construction of the totalizer itself has no particular bearing upon the present invention, and substitute totalizers might be employed provided only that the wheels acted upon by the master wheels are capable of rotating in both directions, one for addition and the other for subtraction. In Figs. 7 to 14 however a suitable totalizer is illustrated in detail, the construction being identical with that shown in Patent No. 782,605 issued to me Feb. 14, 1905. In this totalizer, 23 represents the totalizer shaft which is non rotatably mounted in the totalizer casing 24. Upon this shaft are supported a plurality of sets or groups consisting of five principal parts, to wit: The totalizing wheels 25, the carrying pinions 26, the accumulating wheels 27, the epicyclic pinions 28, and the intermediate wheels 29. Wheels 25, 27 and 29 are all freely rotatable about shaft 23 with the exception of wheel 29^a located at the extreme right to correspond with the units column. This wheel is rigid on a shaft and its function is to form a fixed basis or foundation from which the rotatable parts of the totalizer move their definite amounts.

In each group of parts 30 represents a disk like supporting piece which is splined to the shaft and has at its left portion a cylindrical hub 30^a which forms a bearing whereon the intermediate wheel 29 is freely rotatable. The pin 31 extends toward the left from piece 30 and serves as an axle whereon the carrying pinion 26 is freely rotatable. Said carrying pinion has four long and four short teeth which alternate with each other as best shown in Fig. 8. By means of the long teeth said carrying pinion is alternately locked and rotated by the locking ring 25^a and carrying teeth 25^b respectively of the totalizing wheel 25 at its right. The short teeth serve to make the left portion of the carrying pinion a complete eight toothed gear, and this left portion of the carrying pinion remains permanently in gear action with the internal gear portion 25^c of the next totalizing wheel 25 to the left, by means of the gears 27, 28 and 29 as hereinafter described. As the result the carrying action of pinion 26 is always transmitted to the next higher totalizing wheel 25. Each totalizing wheel 25 has a set of numerical figures on its exterior cylindrical surface and is supported by the contact of its internal cylindrical surface 25^a (which constitutes the aforesaid locking ring) upon the cylindrical edge of the supporting disk 30, said wheels 25 bearing loosely upon

their supporting disks so as to be freely rotatable independently thereof.

The accumulating wheels 27 are plain spur gears having a comparatively large central aperture so that they may set over and be freely rotatable upon the points of the teeth of the intermediate wheels 29. Said accumulating wheels are narrow and their teeth project beyond the circumference of totalizing wheels 25, so that they may be engaged by the master wheels 5 and 6. The totalizing wheel 25^d and supporting piece 30^a (shown at the extreme left of Fig. 7) are slightly modified to impart a finished appearance to the extreme left end of the totalizer.

Extending leftward from each accumulating wheel 27 are two pins 27^a which constitute axles whereon the epicyclic pinions 28 are freely rotatable. Said epicyclic pinions remain in mesh with both the intermediate wheel 29 and the internal gear portion 25^c of wheel 25 for transmitting rotation from one to the other. The aforesaid intermediate wheels 29 are wide faced spur pinions designed to both support the accumulating wheels 27 and also remain in mesh with the carrying pinion 26 and epicyclic pinion 28 at the left and serve to transmit the carrying action of the carrying wheel to the epicyclic pinion and thence to the next higher totalizing wheel 25. As a result of the above described construction of the totalizer it follows that the accumulating wheels 27 are rotatable in either direction and when rotated in one direction will add and when rotated in the opposite direction will subtract.

In operation, the typewriter carriage 2 and hence the totalizer, travels from right to left when viewed from the front of the machine as in Fig. 1, and the traveling is intermittent, that is to say, the carriage and totalizer travel step by step having a rest point or station at the end of every full step as is the case with the most common form of typewriters now in use. As above pointed out, the condition as to whether the totalizer shall add, subtract or not operate depends upon the adjusted position of the totalizer in each rest station thereof; therefore the operator so adjusts the pin 20 in holder 21 that it will contact the proper surface upon the cam arm 17 to shift the totalizer to the proper portion of the rest position. In the present construction if it be considered that the rear shaft 9 is the subtracting shaft and the forward shaft 8 is the adding shaft the operator would, to produce subtraction, cause the totalizer to occupy the most advanced one of its three possible positions at each rest station of totalizer travel. This he would accomplish by adjusting the pin to the position shown in Fig. 6 in which the top of the pin will contact the lowest surface 17^a of cam arm 17. If he desires the machine to add he will adjust pin 20 to the position shown in

Fig. 4, and if he desires the totalizer to remain still he will adjust the pin to occupy an intermediate position as shown in Fig. 5. If there are more than one pair of master wheels 5 as is the case in the machine illustrated, the operator will insert in the holder a pin for each pair of master wheels, and as each pin is independently adjustable the totalizer may be made to add at one pair of master wheels 10 subtract at another pair and remain still at another pair or the order may be varied at the will of the operator. If a plurality of totalizers are employed as illustrated in the drawings, a corresponding number of pin 15 holders will be employed and as these pin holders are out of line with each other and the pins in all of them are independently adjustable, each totalizer may be made to operate independently of every other totalizer, 20 and one may be made to add at a point where its predecessor subtracted and vice versa.

Attention is called to my copending application for patent for calculating machines, filed May 28, 1904, Serial No. 210,158.

25 What I claim as new, and desire to secure by Letters Patent is:

1. In combination, a traveling totalizer, offset non-traveling master wheels occurring in groups of two, in different parallel planes, 30 one of a group producing addition and the other subtraction, and a controlling device for varying the position of the totalizer relatively to the master wheels of a given group to thereby control whether the totalizer shall 35 add or subtract.

2. In combination, a totalizer and a pair of master wheels for operating it, one to add and the other to subtract, said master wheels being laterally offset a fixed amount; and 40 means for varying the relative lateral positions of the totalizer and master wheels for the purpose described.

3. In combination, a traveling totalizer, a pair of offset non traveling master wheels of 45 which pair only one may engage the totalizer at any one time, and a hand adjustable controlling device, substantially as described.

4. In combination, a totalizer adapted to add and subtract, laterally offset master 50 wheels each adapted to operate the totalizer one at a time, and a controlling device operative upon said totalizer to control its lateral position for determining whether the totalizer shall be caused to add or to subtract.

5. In a calculating machine, the combination of a master wheel and a totalizer, one 55 having an intermittent traveling motion relatively to the other, said totalizer having a set of wheels in the different ordinal places 60 thereof adapted to be engaged by the master wheel when in line therewith; and means operative upon said totalizer for producing a slight shift of the totalizer for determining whether or not the totalizer wheels shall be 65 in line with the master wheel when the travel-

ing part of the machine is temporarily at rest.

6. In a calculating machine the combination of a master wheel and a totalizer traveling laterally past it step by step for coming 70 into engagement therewith; and means for laterally shifting said totalizer additionally to and in the same direction with its traveling motion for controlling whether or not the master wheel shall engage the totalizer when 75 the two are approximately in juxtaposition.

7. In a calculating machine the combination of a master wheel; a totalizer having an intermittent traveling movement and having a series of wheels in its different ordinal 80 places for being engaged by said master wheel as they travel past it; and means operative upon said totalizer for predetermineding the lateral position thereof at the different rest points by shifting it laterally to a slight 85 extent for causing the totalizer wheels to stop in line or out of line with the master wheel as the case may be.

8. In a calculating machine the combination of a master wheel; a totalizer having an 90 intermittent traveling motion and having a set of wheels in its different ordinal places for being engaged by said master wheel as they travel past it; and a controlling device adapted to shift said totalizer additionally 95 to its traveling movement for predetermineding whether said master wheel shall or shall not be operative upon said totalizer said controlling device including two coacting parts one traveling relatively to the other for coming 100 into coöperation therewith.

9. In a calculating machine the combination of a master wheel; a totalizer having an intermittent traveling motion and having a set of wheels in its different ordinal places for 105 being engaged by said master wheel as they travel past it; and a controlling device adapted to shift said totalizer additionally to its traveling movement for predetermineding whether said master wheel shall or shall not 110 be operative upon said totalizer said controlling device including a cam and a pin, one traveling in unison with said totalizer.

10. In a calculating machine the combination of a master wheel; a totalizer having an 115 intermittent traveling motion and having a set of wheels in its different ordinal places for being engaged by said master wheel as they travel past it; a cam and a spring for producing a secondary movement of said totalizer in 120 addition to and in the direction of its traveling movement to determine whether the totalizer wheels shall come in line or out of line with said master wheel, and a member adapted to act upon said cam for operating it. 125

11. In a calculating machine the combination of a master wheel; a totalizer having an intermittent traveling motion and having a set of wheels in its different ordinal places for being engaged by said master wheel as 130

they travel past it; a traveling cam and a spring for producing a secondary movement of said totalizer in addition to and in the direction of its traveling movement to determine whether the totalizer wheels shall come in line or out of line with said master wheel, and a stationary member adapted to act upon said cam for operating it.

12. In a calculating machine the combination of a master wheel; a totalizer having an intermittent traveling motion and having a set of wheels in its different ordinal places for being engaged by said master wheel as they travel past it; a traveling cam and a spring for producing a secondary movement of said totalizer in addition to and in the direction of its traveling movement to determine whether the totalizer wheels shall come in line or out of line with said master wheel and a stationary hand adjustable pin adapted to contact said cam for operating it.

13. In a combination, a totalizer capable of addition and subtraction and two master wheels one for causing the totalizer to add and the other for causing it to subtract, said master-wheels being offset from each other so that only one of them can operate said totalizer at any one time; and controlling means whereby the operator may predetermine which of said master wheels shall operate said totalizer.

14. In combination, a totalizer and two master wheels rotating simultaneously, one for producing addition and the other subtraction in said totalizer, said master-wheels being offset from each other so that only one of them can operate said totalizer at any one time; and controlling means whereby the operator may predetermine which of said master wheels shall operate said totalizer.

15. In combination, two laterally offset master wheels rotating simultaneously in opposite directions, and a totalizer adapted to be operated by them one at a time, said totalizer being reversible and located laterally between said master wheels whereby the latter produce opposite effects, one addition and the other subtraction, and controlling means whereby the operator may predetermine which of said master wheels shall operate said totalizer.

16. In combination, a totalizer including a wheel for receiving rotary motion for operating said totalizer; two master wheels adapted to engage said receiving wheel of the totalizer and impart rotary motion thereto in opposite directions said master wheels rotating about parallel axes and in different parallel planes whereby only one of said master wheels can engage said receiving wheel at any one time; and controlling means whereby the operator may predetermine which of said master wheels shall operate said totalizer.

17. In combination, a traveling totalizer including a wheel for receiving rotary motion

for operating said totalizer, two master wheels adapted to engage said receiving wheels and one at a time to impart rotary motion thereto in opposite directions, two parallel shafts each having one of said master wheels fastened thereto; mechanism common to both of said shafts, and a controlling device adapted to produce a secondary travel of said totalizer in the same direction as the main travel whereby the operator may predetermine which of said master wheels shall operate said totalizer.

18. In combination, a traveling totalizer including a wheel for receiving rotary motion for operating said totalizer; two master wheels adapted to engage said receiving wheel on opposite sides thereof one at a time to impart rotary motion thereto, two parallel shafts each having one of said master wheels fastened thereto, mechanism for operating said shafts simultaneously in opposite directions, and a controlling device adapted to produce a secondary travel of said totalizer in the same direction as the main travel, whereby the operator may predetermine which of said master wheels shall operate said totalizer.

19. In a calculating machine the combination of a totalizer having a set of wheels in its different ordinal places for operating said totalizer; and two master wheels for directly engaging and operating said totalizer wheels, in opposite directions, one for addition and the other for subtraction, said master wheels being out of line with each other so that only one of them can engage a wheel of the totalizer at any one time; and controlling means whereby the operator may predetermine which of said master wheels shall engage the totalizer wheels.

20. In combination, a traveling totalizer having a step by step escapement with a rest station at each step; two non traveling master wheels one for producing addition and the other subtraction in said totalizer, said master wheels being located one in advance of the other with reference to the direction of totalizer travel so that the totalizer will come into line with first one and then the other of them, one complete step or ordinal distance of the totalizer being greater than the combined operative width of both of said master wheels; and controlling means whereby the operator may predetermine whether the totalizer when at a rest station shall be opposite one or the other of said master wheels.

21. In combination, a traveling totalizer having a step by step escapement with a rest station at each step; two non traveling master wheels one for producing addition and the other subtraction in said totalizer, said master wheels being located one in advance of the other with reference to the direction of totalizer travel so that the totalizer will come into line with first one and then the other of

- them, one complete step or ordinal distance of the totalizer being greater than the combined operative width of both of said master wheels; a controlling lever operative upon 5 said totalizer to govern its position at a rest station to thereby determine whether it shall when at such rest station be opposite one or the other of said master wheels; and a hand adjustable part for coöperating with said 10 lever to operate the same, said controlling lever and hand adjustable part constituting a controlling device and one of them being stationary and the other traveling in unison with the totalizer.
- 15 22. In combination, a traveling totalizer having a set of gear wheels in its different ordinal places for operating it; an adding and a subtracting master wheel adapted to engage the totalizer gear wheels one after the other 20 as they travel past them, said totalizer having an intermittent traveling movement with a rest station for each full step, and said totalizer being capable of occupying either one of two positions at each rest station 25 whereby any given totalizer wheel may stop in line with one or the other of said master wheels; and controlling means whereby the operator may predetermine in which of said two possible positions at the rest stations the totalizer wheels shall stop.
23. The combination with the keys, key escapement frame and traveling carriage of a typewriter; of a totalizer including a carrying mechanism with a set of gear wheels, 30 in the different ordinal places for operating the same said totalizer traveling in unison with the typewriter carriage, and said totalizer being capable of occupying either one of two positions at each rest station whereby 35 any given totalizer wheel may stop in line with one or the other of said master wheels; and controlling means whereby the operator may predetermine in which of two possible positions at the rest stations the totalizer 40 wheel shall stop.
24. In combination, a totalizer adapted to add and subtract and a pair of laterally offset master wheels one for producing addition and the other subtraction in said 45 totalizer, and means for varying the relative positions, laterally, of said totalizer and master wheels for changing from addition to subtraction and vice versa.
25. In combination, a totalizer capable 50 of occupying two lateral positions and adapted to add and subtract, a pair of laterally offset master wheels, one for causing addition when the totalizer is in one of its said lateral positions and the other for causing sub-

traction when the totalizer is in the other of its said lateral positions, and means for controlling the lateral position of said totalizer to thereby cause it to add or subtract.

26. In combination, a totalizer adapted to add and subtract and having a gear wheel whereby it is operated; companion adding and subtracting master wheels operative one at a time upon said totalizer wheel and offset with a space between them greater than the width of said totalizer wheels; 70 and a controlling device for bringing said master wheels and totalizer gear wheel into line or out of line with each other for the purpose described.

27. In combination, a totalizer adapted to add and subtract and having a carrying mechanism and thin gear wheels for operating the same; companion adding and subtracting master wheels offset with a space between them greater than the width of the thin gear wheels in the totalizer; and a controlling device operative upon said totalizer whereby the operator may predetermine whether any given one of said thin totalizer wheels shall be opposite the adding wheel, or the subtraction wheel or the space between them.

28. In combination, a plurality of traveling totalizers adapted to add and subtract and a pair of laterally offset non traveling master wheels, one for producing addition and the other subtraction in said totalizer as they travel past them; and two independent controlling devices whereby the operator may predetermine independently 95 for each totalizer whether such totalizer shall be operated by said master wheel to add or subtract.

29. In combination, a plurality of traveling totalizers adapted to add and subtract and a pair of non traveling master wheels one for producing addition and the other subtraction in said totalizer, said master wheels being laterally offset a fixed amount with a rest space between them, and two independent controlling devices whereby the operator may predetermine independently 105 for each totalizer whether such totalizer shall add, subtract or not operate when within the operative zone.

In witness whereof, I have hereunto subscribed my name in the presence of two witnesses.

HYMAN ELI GOLDBERG.
